UNITED STATES PATENT OFFICE.

ALFRED N. OLSEN, OF ROCK RAPIDS, IOWA.

PIN-SETTING MECHANISM.

1,347,821.

Specification of Letters Patent. Patented July 27, 1920.

Application filed July 2, 1919. Serial No. 308,081.

To all whom it may concern:

Be it known that I, ALFRED N. OLSEN, a citizen of the United States, residing at Rock Rapids, in the county of Lyon and State of Iowa, have invented certain new and useful Improvements in Pin-Setting Mechanism, of which the following is a specification.

This invention relates to mechanisms for setting bowling pins upon their spots on the floor of a bowling alley and has as its general object the provision of a mechanism for this purpose into which the pins may be placed or thrown and which in its operation will set the pins accurately upon their respective spots in upright position thus avoiding the tedious procedure of manually placing the pins.

The mechanism of the present invention embodies a frame mounted for raising and lowering movement and having a plurality of pin receiving units and one object of the invention is to so construct each of these units that the devices comprising the same will operate to automatically place the pin occupying the same in upright position accurately centered upon its spot, when the frame is lowered, and will after such deposition of the pin automatically release the same so that the position of the pin will not be disturbed when the frame is withdrawn from the pins in an upward direction.

Another object of the invention is to so construct the devices of each pin receiving unit that these devices when in normal or active condition will firmly support or bolster the respective pin when the pin is thrown or placed therein and will yet operate immediately upon lowering of the frame of the device to depositing position, to release the pin and yet support the same firmly in an upright position upon the respective spot.

Another object of the invention is to so construct the devices of each pin receiving unit that when the pin is placed or thrown into the unit it will be supported in upright or vertical position and will continuously maintain said position during the operation of the mechanism as a whole so that in effecting deposition of the pin upon its spot the pin is not in any manner turned, tilted, or subjected to any other motion which would in any way affect its stability when set and released.

Each pin receiving unit embodies coacting

devices for supporting the pin when the latter is deposited therein, one of these devices constituting an abutment for one side of the pin and the other device constituting a bolstering means for the pin, and a further object of the invention is to so construct the bolstering means that the pin engaging member thereof will be caused to promptly and positively recede from the pin when the mechanism is operating to deposit the pin upon its spot.

In the accompanying drawings:

Figure 1 is a view in front elevation of the mechanism embodying the present invention installed in a bowling alley;

Fig. 2 is a vertical front to rear sectional view through one of the pin receiving units, the pin supporting devices thereof being shown in position supporting a pin within the unit;

Fig. 3 is a sectional view taken on the line 3—3 of Fig. 2 looking in a downward direction;

Fig. 4 is a view similar to Fig. 2 but illustrating the manner in which the pin bolstering element is to be moved through its engagement with the floor of the bowling alley to release the pin;

Fig. 5 is a similar view illustrating the positions of the parts when the pin is released and prior to elevation of the pin holding unit;

Fig. 6 is a perspective view of one of the pin bolstering members.

The mechanism embodying the present invention comprises a main frame within which the pin receiving units are located and this main frame is indicated in general by the numeral 1 and as it may be of any suitable construction it has not been shown in detail. Brackets 2 are secured to the opposite sides of the frame and extend laterally therefrom and have secured each to its outer end a rod 3 which extends upwardly from the respective bracket and through suitable upper and lower guides indicated by the numerals 4 and 5 respectively. A diagonal brace 6 is secured at its upper end to each rod 3 and at its lower end to any suitable portion of the frame 1. By this construction and arrangement of parts, the frame 1 is mounted for raising and lowering movement, and in order that the frame may be cushioned in its upward movement, suitable buffer springs 7 may be positioned upon the lower portions of the rods 3 so as to be

compressed between the respective brackets 2 and guides 5 when the frame is moved upwardly. In order to suitably counterweight the frame 1 and its associated parts, cables 5 or other suitable flexible elements 8 are connected as at 9 to the opposite sides of the frame 1 and are passed about pulleys 10 and have connected to their other ends suitable counterweights 11. These weights 11 will 10 be sufficiently heavy to hold the frame 1 in elevated position when all of the ten pins are deposited in the frame and it will be understood, of course, that the frame may be lowered to depositing position upon the floor 15 of the alley, which floor is indicated by the numeral 12, by grasping either of the rods 3 or the frame 1 or any other convenient part of the mechanism and moving the same in a downward direction, and, of course, when 20 the pins have been deposited and the frame or its associated parts have been relieved of this downward pressure, the frame will be automatically returned to the elevated position through the action of the counterweights 25 11. The guides 4 and 5 and also a transverse shaft or bar 13 which carries the pulleys 10, are supported by suitable uprights or standards 14 mounted upon the walls 15 of the alley, as shown in Fig. 1 of the drawings. The bowling pins are indicated each by the numeral 16.

As above stated, the frame 1 may be of any desired construction, and the pin receiving units which are arranged within this 35 frame may be built into the frame or arranged therein in any other suitable manner. As these units are of identical construction, a description of one will suffice for all. Each of the units comprises a box-like body 40 including sides 17, a forward wall 18, and a rear wall 19. The back or rear wall 19 of the unit is vertically disposed and the inwardly presented face thereof, indicated by the numeral 20, is transversely concave preferably on an arc somewhat of greater degree than the arc describing the major circumference of the body of the bowling pin 16 to be received within the unit, as clearly shown in Fig. 3 of the drawings. This back or 45 rear wall constitutes a fixed abutment for the bowling pin, and in order that the pin may be suitably engaged at a point above the point of maximum diameter of its body under conditions to be presently explained, 50 the said wall 19 is provided at its top with an abutment shoulder 21 which may be of metal or any other suitable material and which is preferably set into a rabbet 22 formed in the inner face 20 of the said wall 55 19. This shoulder is secured in place by bolts or other fastening devices 23 and is provided with an inwardly projecting flange 24 having an arcuate inwardly presented edge 25 for engagement with the side of the 60 pin as stated above.

The front wall 18 of the unit is disposed in a plane inclined upwardly and forwardly, and at the rear face of this wall 18, the sides 17 of the unit are formed with correspondingly inclined grooves 26 in which are slidably received the lateral edges of the body of the pin bolstering member which is indicated in general by the numeral 27, the said body being in this manner supported for up and down sliding movement within 70 the forward portion of the unit. It will be understood and particularly by reference to Figs. 2, 4 and 5 of the drawings, that the body 27 of the pin bolstering member is inclined with relation to the plane of the rear 80 wall 19 of the unit and that in the upward sliding movement of the said body 27, the body will recede from the said wall 19. In order to limit the downward movement of the bolstering member, the forward wall 18 of the unit is formed with a slot 28 which extends vertically and opens through the upper edge of the said wall, and the body 27 is provided upon its face which opposes the said wall 18, with a stud 29 designed to normally seat in the lower end of the slot 28 as shown in Fig. 2 of the drawings when the parts are in normal position or more specifically while the bolstering member is in position to bolster and support the pin 16. In 90 order that the bolstering member 27 may be adapted to suitably engage the body of the pin so as to support the same in a centered position, and in order that the bolstering member may readily ride out of engagement 100 with the pin, when operating to spot the same, without disturbing the position of the pin or causing the same to totter, means is provided upon the body of the member 27 as will now be described. Spindles 30 are 105 rigidly secured at their inner ends to a block 31 upon the rear face of the body 27, preferably by providing the said ends of the spindles with attaching tangs 32 which are disposed and secured in grooves 33 in the rear 110 face of the block 31, and these spindles are supported at their outer ends by suitable brackets 34 secured to the said rear face of the body of the member 27, the spindles being disposed with their axes extending at 115 diverging lines as clearly shown in Fig. 3 of the drawings. The numeral 35 indicates concave antifriction rollers which are rotatably mounted upon the spindles 30 and which may be of fiber or any other suitable 120 material, the curvature of the concave peripheries of the rollers being such as to adapt these faces to snugly fit and conform to the contour of the body of the pin to be supported. The disposition of the rollers 35 is such that they will engage the forward side of the pin at spaced points located at opposite sides of the front to rear median line of the body of the pin disposed within the unit, and inasmuch as the bolstering 125 130

member 27 will recede from the abutment 19 as the said member slides upwardly in the frame of the unit, the rollers 35 will be correspondingly moved with relation to the 5 said abutment 19. When the bolstering member 27 is in the lowered position shown in Fig. 2 of the drawings, the maximum distance between its rollers 35 and the concave face 20 of the abutment wall 19 will be less 10 than the maximum diameter of the body of the pin 16 so that when the pin is dropped or thrown into the unit, it will assume substantially the upright position shown in Fig. 2 and will be supported in this position 15 until the apparatus is operated to spot the pins.

The body of the bolstering member 27 is provided with spaced downwardly extending legs 36 and as the frame of the structure 20 is lowered for the purpose of spotting the pins, the lower ends of the said legs 36 will come into engagement with the surface of the floor or alley, as clearly shown in Fig. 4 of the drawings, and upon continued 25 downward movement of the frame 1, the bolstering members will be moved upwardly within their respective units slightly elevating the respective pins until they come into engagement at the rear sides of their bodies 30 with the arcuate edges 25 of the respective shoulders 21. At such time, the maximum distance between the rollers 35 and the concave or abutment face of the wall 19 of the respective unit will be approximately equal 35 to the maximum diameter of the body of the respective pin but also at this time the lower extremities of the legs of the bolstering members will still project a short distance below the lower edges of the walls of the 40 unit. As the lowering of the frame 1 is completed, the bolstering member of each unit will be further moved in an upward direction carrying with it the respective rollers which, as they ride upwardly along the forward side of the body of the pin, permit the 45 pin to drop from the position shown in Fig. 4 to the position shown in Fig. 5, in which latter position the pin will be properly spotted upon the floor of the alley. It will 50 be understood by reference to Fig. 4 that the two rollers engage the forward side of the pin at the opposite sides of the front to rear median line thereof and the rear side of the body of the pin is in engagement at 55 a single point in said line with the concave face 20 of the abutment member 19, the rear side of the pin at the upper portion thereof being also in engagement with the arcuate edge of the shoulder 21 so that the pin is 60 spotted accurately in upright or vertical position which it will maintain as it is dropped to the position shown in Fig. 5. After the pins have been spotted in the manner stated and as shown in Fig. 5 of the drawings, the 65 frame 1 is raised and as it raises carrying

with it the pin receiving units, the rollers will remain in engagement with the forward sides of the respective pins and the said pins will remain at their rear sides in engagement with the concave faces of the abutment 70 members 19 of the respective units and will thus be steadied and prevented from tottering. Of course, as the units are further elevated, the pin bolstering members will gradually resume the position shown in Fig. 2 of 75 the drawings until finally they are lifted entirely clear of the respective pins.

Having thus described the invention, what is claimed as new is:

1. In pin setting mechanism, means to receive and support a pin in upright position and including a bolstering member movable in a direction to recede from the pin and in so moving operable to seat the same without a change in the position of the pin and to 80 steady the pin upon receding therefrom.

2. In pin setting mechanism, means to receive and support a pin including a member 85 slidable in an up and down direction and arranged in lowered position to support the pin in upright position, the said member having a floor engaging part to provide for movement of the member in an upward direction and in a manner with relation to the pin to set the said pin without a change in 90 the position of the pin.

3. In pin setting mechanism, means to receive and support a pin in upright position and including fixed and movable coacting pin engaging devices, the movable device being arranged in active position to engage the body of the pin below its line of maximum diameter and in released position to engage the body of the pin substantially at 95 said line and operable to set the pin without 100 a change in its position.

4. In pin setting mechanism, a supporting means mounted for raising and lowering movement, and a pin bolstering member mounted thereon and movable in a downward direction to active position and in an upward direction to inactive position, and means providing for automatic movement of the said member to inactive position upon lowering of the supporting means.

5. In pin setting mechanism, means to receive and support a pin to be set comprising a relatively fixed abutment member, and a gravity actuated bolstering member bodily slidable in an up and down direction and coacting therewith and having a floor engaging part to provide for its movement in an upward direction to release the pin when the means is lowered to spotting position.

6. In pin setting mechanism, means to receive and support a pin to be set comprising a relatively fixed abutment member, and a bolstering member mounted for up and down sliding movement and guided in its upward movement to recede from the plane 125 130 135

of the abutment member, the said bolstering member having a floor engaging part.

7. In pin setting mechanism, means for receiving and supporting a pin to be set comprising an upright relatively fixed abutment member, and an inclined bolstering member supported for up and down sliding movement and located opposite the said abutment member and arranged in its upward movement to recede from the plane thereof.

8. In pin setting mechanism, means for receiving and supporting a pin to be set comprising an upright relatively fixed abutment member, a bolstering member slidably supported for up and down movement in a plane inclined upwardly away from the plane of the abutment member, the said bolstering member having a floor engaging part.

9. In pin setting mechanism, means for receiving and supporting a pin to be set comprising an upright relatively fixed abutment member having a concave abutment face to engage one side of the body of the pin, and a bolstering member mounted for movement in a direction receding from the said face of the abutment member and having anti-friction rollers to engage the opposite side of the pin at spaced points.

10. In pin setting mechanism, means for receiving and supporting a pin to be set comprising an upright relatively fixed abutment member having a concave abutment face to engage one side of the body of the pin, and a bolstering member mounted for movement in a direction receding from the said face of the abutment member, and having anti-friction rollers to engage the opposite side of the pin at spaced points, the said rollers having concave peripheries to conform to the curvature of the body of the pin.

11. In pin setting mechanism, means to receive and support a pin to be set comprising a relatively fixed abutment member having a concave abutment face to engage one side of the pin to be set, a fixed member located opposite the abutment member, a bolstering member slideable with relation to the said fixed member, and coacting means upon the bolstering member and the said fixed member for limiting the downward movement of the bolstering member by gravity.

12. In pin setting mechanism, means for receiving and supporting a pin to be set

comprising a relatively fixed abutment member having a concave abutment face to engage one side of the body of the pin to be set and having an arcuate shoulder overhanging said face to engage the neck portion of the pin, and a movable floor engaging bolstering member located opposite and movable with relation to the said abutment member.

13. In pin setting mechanism, means for receiving and supporting a pin to be set comprising a pin receiving unit including side walls and oppositely located connecting walls, one of the said connecting walls constituting a relatively fixed abutment to be engaged by one side of the pin to be set, the other connecting wall being disposed in a plane inclined upwardly and away from the first mentioned connecting wall, and a bolstering member mounted in the unit for sliding movement against the inner face of the last mentioned connecting wall and having a floor engaging portion projecting below the unit, whereby upon engagement of the said portion with a floor in the lowering movement of the unit, the said bolstering member will be moved upwardly and in a direction to recede from a pin bolstered thereby.

14. In pin setting mechanism, means for receiving and supporting a pin to be set comprising a pin receiving unit including side walls and oppositely located connecting walls, one of the said connecting walls constituting a relatively fixed abutment to be engaged by one side of the pin to be set, the other connecting wall being disposed in a plane inclined upwardly and away from the first mentioned connecting wall, a bolstering member mounted in the unit for sliding movement against the inner face of the last mentioned connecting wall and having a floor engaging portion projecting below the unit, whereby upon engagement of the said portion with a floor in the lowering movement of the unit, the said bolstering member will be moved upwardly and in a direction to recede from a pin bolstered thereby, the said inclined connecting wall having a vertically extending slot therein, and a pin projecting from the bolstering member into said slot and engageable with the lower end wall of the slot whereby to limit the downward movement of the bolstering member.

In testimony whereof I affix my signature.

ALFRED N. OLSEN. [L. S.]
